UNITED STATES PATENT OFFICE.

ALFRED H. NEWPHER, OF CHICAGO, ILLINOIS, ASSIGNOR TO THE ADAMS & WESTLAKE COMPANY, A CORPORATION OF ILLINOIS.

WINDOW.

1,096,556.

Specification of Letters Patent.

Patented May 12, 1914.

Original application filed March 12, 1910, Serial No. 548,895. Divided and this application filed August 8, 1910. Serial No. 576,185.

To all whom it may concern:

Be it known that I, ALFRED H. NEWPHER, a citizen of the United States, and resident of Chicago, county of Cook, and State of Illinois, have invented certain new and useful Improvements in Windows, of which the following is a specification, and which are illustrated in the accompanying drawings, forming a part thereof.

10 The invention relates to improvements in windows, and more particularly to windows having metal frames, its object being to provide improved means for guiding the sash in vertical ways in the frame stiles.

15 This specification is a division of the specification of my pending application, filed March 12, 1910, Serial No. 548,895.

20 The invention consists in a structure such as is hereinafter described and as illustrated in the accompanying drawings, in which—

25 Figure 1 is a detail perspective of a lower corner of the window frame; Fig. 2 is a detail plan section through the frame stile and the sash; and Fig. 3 is a similar figure showing a slight modification.

The sill of a window frame is shown at 10 and its stiles at 11, 12.

30 The invention is represented as applied to railway cars having sheet metal bodies, a part of the outer wall of the car being shown at 13.

35 At 14 is shown an outer, and at 15 an inner, guide stop for the sash, the drawings showing the window as being provided with two sash 16, 17.

40 At 18 there is shown a vertical bar attached to the frame stile, and upon this bar is mounted a sheet metal plate 19, which is held in place by means of screws, as 20, these screws serving also in the present instance as securing means for the bar 18.

45 The marginal portions 21, 22 of the plate 19 are folded outwardly substantially perpendicular to the body portion of the plate, and are then folded backwardly to the surface of the stile plate 12. These folded por-

tions 21, 22 form yielding stops coöperating with the stops 14, 15 to provide run-ways for the sash 16, 17, and the intermediate portions of the plate afford a guide-way for a 50 dust screen, (not shown).

In the modification shown in Fig. 3 in lieu of the single plate 19 there is shown a pair of plates 23, 24 each having a body portion of the width of the bar 18, one of 55 these plates lying directly upon the outer face of the bar and the other being applied to the outer face of the former plate, both being secured by the screws 20. Each plate is folded outwardly as shown, as at 25, 26, 60 and then backwardly to the face of the stile plate 12, thus providing the same form of spring guides as are present in the construction illustrated in Fig. 2, and differing only in that the pair of stops is composed of two 65 over-lapping plates instead of a single plate. It is obvious that in the construction shown in Fig. 3 but a single one of these spring stops may be employed should the window be provided with but one instead of a pair 70 of sash.

The sash 16 and 17 may be of any desired construction but are here shown as of metal and as taking the form illustrated in the application of which this is a division. It is 75 also obvious that the bar 18 may be dispensed with, the body portion of the plate 19, or of the plates 23, 24, being secured directly to the stile plate 12.

I claim as my invention:

1. In a window frame, in combination, a stile plate, fixed stops for engaging the remoter faces of a pair of sash, a double stop for engaging the adjacent faces of the sash and having yielding outwardly bowed and 85 recurred margins forming a guide groove for a screen and yielding leaves for engaging the sash.

2. In a window frame, in combination, a frame stile, a pair of sash guides fixed to the 90 stile, one thereof being a spring metal plate and being turned outwardly from its line of

attachment to the stile, its margin being bowed inwardly toward the stile and forming a yielding bearing for the sash.

3. In a window frame, in combination, a stile plate, a pair of stops for engagement by the remoter faces of a pair of sash, and a central stop comprising a U-shaped sheet metal plate secured to the stile, the outer

margins of its side members being folded back to form leaves for engaging by their flat faces the adjacent faces of the two sash.

ALFRED H. NEWPHER.
